Patented Jan. 5, 1915.

UNITED STATES PATENT OFFICE.

LEWIS ANSON RICE, OF ALLENtown, PENNSYLVANIA, ASSIGNOR TO JOHN D. SHARPE,
OF THETFORD MINES, QUEBEC, CANADA.

APPARATUS FOR DRYING ASBESTOS AND THE LIKE.

1,123,377.

Specification of Letters Patent.

Patented Jan. 5, 1915.

Application filed April 7, 1914. Serial No. 830,294.

To all whom it may concern:

Be it known that I, LEWIS A. RICE, a citizen of the United States of America, residing at Allentown, State of Pennsylvania, 5 United States of America, have invented certain new and useful Improvements in Apparatus for Drying Asbestos and the like; and I do hereby declare that the following is a full, clear, and exact description 10 of the same.

My invention relates particularly to the drying and cleaning of asbestos bearing rock and has for an object to bring the fibers into direct contact with a current of 15 heated air or gas and to provide a new and improved drying apparatus to secure the advantageous results of, first, more thoroughly and efficiently drying the asbestos than heretofore; second, avoiding charring of the 20 fibers due to excessive heating and, third, producing a more desirable grade of fiber than formerly.

Further objects and advantages will be hereinafter more fully described and particularly pointed out in the claims. For 25 full comprehension, however, of my invention reference must be had to the accompanying drawing forming a part of this specification in which similar reference 30 characters indicate the same parts and wherein:

Figure 1 is an elevation, partly in section, of a drier constructed according to my invention; Fig. 2 is a vertical section taken 35 on line 2—2 Fig. 1; Figs. 3 and 4 are, respectively, a plan and a side elevation illustrating the construction of the supports for 40 the grid bars; Fig. 5 is an enlarged horizontal section on line 5—5 Fig. 2; and Fig. 6 is a detail perspective view illustrating the particular arrangement of the grid bars.

Heretofore the drying and cleaning of asbestos has not been entirely satisfactory for the reason that after the cleaning and 45 drying process it has been found that it was somewhat off color, thus indicating the presence, still, of certain impurities, such as clay, dust, etc., and furthermore the asbestos has frequently been heated to such an extent that it became charred or so very brittle

that its commercial value was considerably reduced.

I propose to avoid the above mentioned disadvantages by causing a current of heated air, gas or the like to come into direct 55 contact with the asbestos in a suitable manner such as may be effected, for example, by means of my improved drier, the construction of which I will describe in connection with my improved drying and cleaning 60 method.

A suitable structure of any desired form may be utilized, that shown in the drawings consisting of a tower 2 of square cross section, provided with manholes 3 at suitable intervals and having a discharging hopper 4 at or near the bottom thereof and a chute 5 at the top for feeding the ore to the tower down which it drops, the ore being conveyed to the inlet chute 5 preferably by an elevator 6. In the tower, below the inlet 5, an arrangement of grids or baffles is formed through which the asbestos filters and is spread out as it descends and I prefer to form this grid of vertically and horizontally spaced bars 7 arranged in vertically disposed sets each of which consists of two rows of substantially parallel bars in staggered relation and extending across the tower from side to side, alternate sets being 75 angularly disposed with relation to each other, that is the bars of each set are arranged preferably at right angles to the bars of adjoining sets. The bars 7 are preferably of T-iron and removably mounted in 80 the tower by means of horizontal plates 8, arranged in vertically disposed pairs alternately embedded or otherwise suitably secured to different opposing interior side walls of the tower, such supports being 85 formed with extensions 9 vertically slotted as at 10. The T-irons are supported at their ends by the plates 8, being lowered into position with their webs extending 90 downwardly and located in the slots 10 and 95 their flanges resting upon the extensions 9. The bars are free to be moved in an upward direction away from their supports and removed from the tower through the manholes 3.

To dry the asbestos as the ore containing the same filters down through the grids I direct a current of heated air or gas in an opposite direction, that is, upward through 5 the tower to an outlet port 11 at the top of the latter through which the gas and impurities or waste products pass, the velocity of the air current being regulated proportionately to the quantity of material passing 10 down through the tower while the chute 5 is provided with a back pressure valve 12.

At or near the bottom of the tower I provide a furnace 13 which communicates with the tower and supplies the heated air directly to the interior of the same by means of a passage 14 and although any approved means may be provided to force the heated air through the tower, I prefer to utilize a blower 14^a which communicates with the 20 firebox of the furnace as at 15. The arch or roof 16 of the firebox is formed with one or more passages 17 communicating with the exterior of the furnace, extending across the firebox from front to rear and communicating 25 at their rear or inner ends with a common chamber 18 from which latter a pipe 19 leads to the intake of the blower casing so that as the air is drawn in through the passages 17 it is preheated before being forced 30 into the firebox with the result that the drying of the asbestos is performed in a highly efficient manner.

The asbestos is dropped from the chute 5 upon the grids and descends in an intermittent manner through a staggered path, the falling mass being retarded somewhat and opened up and thus thoroughly dried by the ascending heated gases before dropping into the discharge hopper 4.

40 The provision of means for preheating the air and then increasing the heat of the same by passing it through the firebox of the furnace and the regulation of the heated current enables the fibers to be subjected to a flash heat and thus avoid any prolonged heating and consequent charring of the fibers while the heated air coming in direct contact with the fibers and acting upon the moisture therein has the effect of forming 45 steam which thoroughly cleans the fibers so that when the latter are discharged they are what may be termed bleached and therefore 50 of high commercial value.

What I claim is as follows:

55 1. In an asbestos drying apparatus, the combination with a tower adapted to have the asbestos passed therethrough, of a furnace, the firebox of which is in direct communication with the tower, a passage in the 60 furnace wall communicating at its outer end with the exterior of the furnace and extending across the top of the firebox and a device, in communication with the inner end

of the passage and with the firebox, for drawing air through such passage and forcing the air through the firebox into the tower.

2. In an asbestos drying apparatus, the combination with a tower, of a furnace, the firebox of which is in direct communication 65 with the tower, passages in the furnace wall communicating at their outer ends with the exterior of the furnace and extending across the top of the firebox, a chamber having the inner ends of the passages communicating 70 therewith, a blower, a pipe leading from said chamber to the blower and a pipe leading from the blower to the firebox.

3. An asbestos drying apparatus having a tower adapted to have the asbestos dropped 75 therethrough and a furnace in direct communication with the tower, such tower having an arrangement of grids therein comprising vertically disposed sets of bars, each set consisting of two rows of substantially 80 parallel bars in staggered relation, alternate sets being angularly disposed with relation to each other.

4. An asbestos drying apparatus having a tower adapted to have the asbestos dropped 85 therethrough and a furnace in direct communication with the tower, such tower having an arrangement of grids therein comprising vertically disposed sets of bars, each set consisting of two rows of substantially 90 parallel bars in staggered relation, the bars of each set being arranged at right angles to the bars of adjoining sets.

5. An asbestos drying apparatus comprising a tower having an asbestos ore inlet and 95 a waste product outlet at the top and a discharge hopper at the bottom, supports secured to the interior sides of the tower and having vertically slotted inward extensions, the supports being arranged in vertically 100 disposed pairs alternately secured to different opposing sides of the tower, T-iron bars resting upon the supports and having their webs located in the vertical slots of the latter, a furnace, the firebox of which is in 105 direct communication with the tower near the bottom thereof, passages communicating at their outer ends with the exterior of the furnace and extending across the top of the firebox, a chamber having the inner end of 110 the passages communicating therewith, a blower, a pipe leading from said chamber to the blower and a pipe leading from the blower to the firebox.

6. An asbestos drying apparatus having a 115 tower adapted to have the asbestos dropped therethrough and a furnace the firebox of which is in direct communication with the tower, such tower having an arrangement of grids therein comprising vertically disposed 120 sets of bars, each consisting of two rows of 125

substantially parallel bars in staggered relation, alternate sets being angularly disposed with relation to each other, means for passing air through the firebox into the tower and between said bars and means for heating such air previous to its entry to the firebox.

In testimony whereof, I have signed my name to this specification, in the presence of two subscribing witnesses.

LEWIS ANSON RICE.
